(57) **CLAIM**

The ornamental design for a medical device controller, substantially as shown and described.

DESCRIPTION

FIG. 1 is a top front perspective view of the controller;

FIG. 2 is a front view of the medical device controller;

FIG. 3 is a right side view of the medical device controller;

FIG. 4 is a top back perspective view of the medical controller;

FIG. 5 is a top front perspective view of the medical device controller;

FIG. 6 is a top view of the medical device controller;

FIG. 7 is a back view of the medical device controller;

FIG. 8 is a left side view of the medical device controller; and,

FIG. 9 is a bottom view of the medical controller.

The broken lines are included for the purpose of illustrating portions of the medical device controller that form no part of the claimed design.
